MAGNETIC COMPRESSION SYSTEM

Dorothy L. Blaney, Los Angeles, Calif., assignor to Radio Corporation of America, a corporation of Delaware

Application April 26, 1952, Serial No. 284,595

8 Claims. (Cl. 179—100.2)

The invention relates to magnetic sound recording and reproduction, and particularly to a system for automatically obtaining compression of the signal during recording. This application is a continuation-in-part of my application, Ser. No. 99,986, filed June 18, 1949, now abandoned.

In the production of motion pictures, wherein a concomitant sound for the picture is recorded on a photographic sound track which is reproduced during the projection of the picture, compression of the higher amplitudes of the signal has been found desirable for several reasons. For instance, since the sound track area has a definite level range where the relationship between input and output is linear, a wider range may be recorded by compressing the higher amplitudes of a signal at a predetermined rate. Compression also provides a safety feature in the event the level suddenly increases beyond the upper range of the film. Furthermore, a compressed signal has been found to be more intelligible when reproduced in the average theater at high levels, even though some distortion is introduced in the wave shape of the signal.

With the advent of magnetic recording in the production of motion pictures, it has also been found desirable to compress the signal at some point in the recording channel. Although this compression may be done electronically, the present invention is directed to a system for automatically compressing the high level signals by operating either on the shoulder of the magnetic characteristic curve of the magnetic record medium, or on the shoulder or saturation portion of the recording head characteristic curve. When using the core characteristic curve, variations in the width of the rear gap of the core of the magnetic head will result in various degrees of compression. Also, a direct current of different values through the head winding may be used to shift the point at which compression occurs and the amount of compression. The system may be set manually to provide different signal levels at which compression occurs or begins and to provide certain amounts of compression above said levels, and the variations may be accomplished automatically with the variation in the average value of the signal level.

The principal object of the invention, therefore, is to facilitate the recording of magnetic sound records.

Another object of the invention is to provide an improved system for obtaining compression in the recording of magnetic records.

A further object of the invention is to provide an improved system for automatically compressing high amplitudes of a signal being recorded magnetically either by fixed settings or in accordance with the average variations in the signal level.

Although the novel features which are believed to be characteristic of this invention will be pointed out with particularity in the appended claims, the manner of its organization and the mode of its operation will be better understood by referring to the following description, read

in conjunction with the accompanying drawings, forming a part hereof, in which:

Fig. 1 is a graph illustrating the operation of the compression system of the invention.

5 Fig. 2 is a graph showing the relationship between input and output obtainable with the invention.

Fig. 3 is a view of a magnetic recording head constructed in accordance with the invention, and

10 Fig. 4 is a block diagram of a magnetic sound recording system embodying the invention.

Referring now to the graph shown in Fig. 1, 5 and 6 represent, for purposes of illustration, a magnetic characteristic curve between either the current in the recording head coil and the leakage flux in the air gap of the core 15 of the head, or the characteristic curve between the flux introduced into a magnetic record carrier and the magnetism produced therein. In the normal manner of recording, a magnetic bias is applied to the coil, which utilizes the range which extends over only the straight portions 20 of the curve, as shown between points *a*—*b* and *c*—*d*. There is thus provided a linear relationship between the variations in the signal level and the magnetism produced in the record carrier. To illustrate this action, an audio wave 7—7' is shown combined with a high frequency carrier bias wave 8, shown in full lines, the maximum level of the audio wave shifting the peaks of the bias wave different amounts between points *a*—*b* and *c*—*d*, in accordance with the amplitude of the audio signal. If the amplitude never goes beyond points *a*, *b*, *c*, and *d*, 25 a linear relationship will always exist between the input and output signal, as shown by the final output wave in full lines 10, which is made up of the waves shown by dotted lines 11 and 12. This linear relationship is illustrated by rectilinear curve 14 in Fig. 2.

30 35 If it is now desired to obtain compression of the wave 7—7', the level of the wave as impressed on the coil of the head may be increased, or the level of the bias wave 8 may be increased. The result of increasing the level of the audio wave is illustrated by proportionately increasing

40 45 the peaks of wave 7—7', as shown by the dotted lines 16—16'. By this amount of audio level increase, the degree of compression obtained is in accordance with the curvature of the characteristic curve 5—6, between points *b*—*e*, *a*—*f*, *c*—*g* and *d*—*h*. The resulting compressed wave is now shown by solid curve 18 made up of dotted wave curves 19 and 20. If the wave were not compressed, it would appear as the combination of wave curves 19 and 20 with the additional solid line peaks 13 and 17 obtained by extending the straight portions of curve 5—6,

50 55 as shown at 9 and 15. For greater amounts of compression, the audio signal level could be proportionately increased to utilize more of the curved shoulder portions of the curve 5—6. Thus, various degrees of compression are obtainable, as illustrated by curves 40, 31, and 32 in Fig. 2, it being noted that the output wave is substantially equally compressed for equally high peaks, since the wave 8 and wave 7—7' combine about the points 34 and 35, mid-way on the straight portions of curve 5—6.

Various degrees of compression may also be obtained 60 by the use of the magnetic characteristic curve of the magnetic head. Referring now to Fig. 3, a film 21 is shown passing over the recording gap 22 of the core sections 23 and 24 of a recording head, the rear gap of the head being shown at 25. The head has the regular winding 26 thereon. By increasing the level of a direct current in the winding 26, or by pivoting the cores 23 and 24 near gap 22 and adjustment of the gap 25 by screw 27 in ears 28 and 29 on the rear ends of cores 23 and 24, respectively, the strength of the leakage flux into the record medium may be varied for average signal levels 65 to provide different degrees of magnetization of the me-

dium, depending upon the average level of the audio signal or bias current.

When the level of the bias current or wave 8 is increased, it shifts the points 34 and 35 toward points *b* and *d*, respectively, and thus, compression may occur over only the end or shoulder curved portions of the characteristic curve and the positive peaks of the audio wave, the audio negative peaks not going beyond points *a* and *c*, depending upon the level of the audio signal. This increased level also introduces an increased amount of compression into a signal of any given amplitude.

Referring now to Fig. 4, a standard commercial form of magnetic recording system is illustrated. A signal source 40 feeds a signal amplifier 41 having a level control such as a potentiometer 42. The output of the signal amplifier is fed to a mixer 44 and then to a magnetic recorder 45, which may have any standard type of recording head or of the type shown in Fig. 3. In the standard magnetic recorder, a bias oscillator 46 is used, oscillator 46 being connected to a bias amplifier 47 having a level control such as a potentiometer 48. The output of the amplifier 47 is fed to the mixer 44 as is well-known in the art. The amplifier 47 may be of the variable gain type, although when the gain is not varied, it functions in the manner of a normal fixed gain amplifier.

Shown bridged across the output of the signal amplifier 41, is a circuit having a switch 50 therein and a circuit having a switch 51 therein. When the switch 50 is closed, a portion of the output from the signal amplifier 41 is fed to a rectifier 53 connected with bias amplifier 47. When switch 51 is closed, a portion of the output from signal amplifier 41 is fed to a rectifier 54, the output of which is connected to the magnetic recorder 45, and particularly to the windings of the recorder head. A source of direct current is shown at 56 which may be connected to the windings of the magnetic head in recorder 45 when the switch 57 is closed. The level of the direct current is set by a potentiometer 58.

The above recording system may function in several ways, depending upon the operation of the switches 50, 51, and 57. In normal operation, these switches are open, and the amount of compression is then determined by the setting of potentiometer 42 which increases the level of the audio signal, such as shown at 7 and 7' in Fig. 1. The point at which compression begins is controlled by the setting of the potentiometer 48 in the bias amplifier 47, although this adjustment also has an effect on the amount of compression introduced in the signal record. Thus, as described above, the point at which compression occurs along the characteristic curve 14 of Fig. 2 and the amount of compression recorded with signal amplitude may be controlled as shown by curves 30, 31, and 32.

If it is desired to variably shift the point at which compression occurs in accordance with the average value of the signal amplitude, the switch 50 may be closed. A portion of the signal is now rectified and varies the gain of bias amplifier 47 with the average value of the signal amplitude, thus shifting the point of compression as the amplitude varies. This system may function in two ways. First, increased signal levels may increase the output of the bias amplifier, thus moving the point at which compression occurs up on the curve 14. Secondly, the reverse connection may be made so that increased signal levels decrease the output of the bias amplifier, thus shifting the point at which compression occurs downwardly on the curve 14.

Another manner of operation is when the switch 51 is closed and switch 50 opened. With these connections, part of the signal is rectified and impressed on the windings of the recording head, thus increasing the saturation and shifting the point at which compression occurs, and also varying the amount of compression at certain amplitudes. Thus, the compression will vary with the average value of the signal. However, if it is desired to provide

a fixed point at which compression occurs and a fixed amount of compression for a certain average level, switches 50 and 51 are opened and switch 57 closed, and a fixed amount of direct current will then be applied to the windings, according to the setting of potentiometer 58. With both switches 50 and 51 closed and switch 57 open, the magnetic film medium and the head core material both coat to control the compression.

The above recording system, therefore, utilizes the characteristics of the magnetic recording medium or the characteristic curves of the core of a recording head, or both to provide any particular amount of compression of a signal. This is particularly desirable, as pointed out above, for subsequent reproduction, as it has been found that different types of signals require different treatments from the compression standpoint.

I claim:

1. A magnetic sound recording system for recording a compressed signal on a magnetic medium from a source 20 of signal currents comprising an amplifier for said signal currents connected to said source, a source of bias frequency currents, an amplifier for said bias frequency currents, means for mixing said signal currents and said bias frequency currents, a magnetic recording head on which 25 said mixed signal currents and said bias frequency currents are impressed, said head being adapted to be brought into contact with said magnetic medium, means in said signal amplifier for adjusting the level of said signal currents with respect to the level of said bias frequency currents to determine the amount of compression of said signal currents as recorded, and means in said bias frequency current amplifier for varying the level thereof with respect to the level of said signal currents to determine the level of said signal currents at which said compression 35 thereof begins.

2. A magnetic sound recording system in accordance with claim 1, in which a circuit is provided between the output of said signal current amplifier and said bias frequency current amplifier, said circuit including a rectifier for obtaining a current varying with the variations in the average value of said signal currents for varying the level of said bias frequency currents in accordance therewith.

3. A magnetic sound recording system in accordance with claim 1, in which a circuit is provided between the output of said signal amplifier and said magnetic head, said circuit including a rectifier for obtaining a current varying with the average value of said signal currents for varying the current in said magnetic head.

4. A magnetic sound recording system in accordance with claim 1, in which a direct current source is provided, together with a circuit interconnecting said source and said magnetic head for providing a predetermined value of direct current to said head for effecting the point of compression of said signal currents and the amount of compression thereof.

5. A system for obtaining compression in the recording of a signal on a magnetic medium from a signal source comprising means for amplifying signal currents from said source, a source of bias frequency currents, means for amplifying said bias frequency currents from said source, means for mixing said signal currents and said bias frequency currents, a recording head adapted to be brought in contact with said magnetic medium and on which said mixed signal currents and bias frequency currents are impressed to magnetize said magnetic medium in accordance with the variations in said mixed currents, and means for controlling the amplitude of said signal and bias frequency currents with respect to one another to vary the amount of compression of said signal currents and the level of said signal currents at which compression thereof occurs.

6. A system in accordance with claim 5, in which is provided means for controlling the level of said bias frequency currents in accordance with the instantaneous

variations in the average value of said signal currents to vary the amplitude of said signal currents at which compression of said signal currents begins.

7. A system in accordance with claim 5, in which said recording head has an adjustable rear gap for varying 5 the amount of compression and the level of the signal currents at which compression occurs.

8. A system in accordance with claim 5, in which a direct current source is provided for energizing said head to vary the amount of compression and the level of the 10 signal currents at which compression occurs.
